UNITED STATES PATENT OFFICE

131,647

DESIGN FOR AN ELECTRIC IRON OR SIMILAR ARTICLE

Irving Edelman, Brooklyn, N. Y.

Application May 19, 1941, Serial No. 101,005

Term of patent 3½ years

To all whom it may concern:

Be it known that I, Irving Edelman, a citizen of the United States of America and resident of the Borough of Brooklyn, county of Kings, city and State of New York, have invented a new, original, and ornamental Design for an Electric Iron or Similar Article, of which the following is a specification, reference being had to the accompanying drawing, forming a part thereof.

In the drawing:

Figure 1 is a top plan view of an electric iron or similar article showing my new design;

Figure 2 is a side elevational view thereof;

Figure 3 is a front elevational view thereof;

Figure 4 is a rear elevational view thereof;

Figure 5 is a rear elevational view of the control knob shown in Figure 2;

Figure 6 is a front elevational view of said knob; and

Figure 7 is a top plan view of the knob.

The dominant features of the design reside in the portions shown in full lines.

I claim:

The ornamental design for an electric iron or similar article, as shown and described.

IRVING EDELMAN.
